Atty's.

UNITED STATES PATENT OFFICE.

ALBERT M. PIGEON, OF NORRISTOWN, PENNSYLVANIA, AND OR TO WILDMAN MFG. CO., OF NORRISTOWN, PENNSYLVANIA, A CORPORATION OF PENNSYLVANIA.

SPRING-BEARD NEEDLE.

1,230,323,

Specification of Letters Patent. Patented June 19, 1917.

Application filed June 6, 1916. Serial No. 161,985.

To all whom it may concern:

Be it known that I, ALBERT M. PIGEON, a citizen of the United States, residing at Norristown, Pa., have invented certain new 5 and useful Improvements in Spring-Beard Needles, of which the following is a specification.

It is the object of my invention to provide a spring beard needle which will be 10 free from the objection of crystallization at the bend of the nose or head, this part being relatively stiff and non-flexible in respect to the beard and that part of the stem which lies back of the beard, both of which portions will be flexible to bend in the act of 15 pressing, and in knitting with tight stitches, enabling the needle to pass through such stitches without subjecting them to undue strain.

20 Another object of the invention is to provide for a large opening within the nose or head to permit the yarn to reeve through readily and also to allow the passage of knots and bunches.

25 The needle is shown in the accompanying drawing in which,

Figure 1 is a front view of a needle embodying the invention.

Fig. 2 is a side view of the new needle.

30 Fig. 3 is a view similar to Fig. 2 with the needle beard closed, and a tight loop thereon.

Fig. 4 is a view of the complete needle.

The needle at that portion back of the stem is tapered by swaging as indicated by 35 the full line *a* and the dotted line *a'*. This tapered part at the back is slabbed off or milled out after tempering, making this part, when the needle is formed, as thin as the beard 3. The cross sectional shape of 40 this thinned back is indicated by the cross section *b*, and the thickness and shape of the beard at the corresponding height is indicated by the cross section at *c*. The head or nose *A* of the needle is circular in 45 cross section and is of about fifteen-thousandths of an inch in diameter, while the stem back of the beard and the beard itself at the points *b*, *c*, are about ten thousandths thick. The nose therefore is stiffer than the

back or beard and during pressing the beard 50 will bend and also the back but no bending will take place in the nose itself and therefore there will be no crystallization at this point, and the breaking off of the needle beard will be prevented. The nose being 55 circular in cross section allows the yarn to reeve through it freely and it will take knots or bunches without offering obstruction thereto. Because both the back and beard can flex tight knitting can be done 60 without straining the yarn and I have shown in Fig. 3 a tight loop at *d* on the closed beard.

The inner or front side of the needle back, or that portion in rear of the beard is 65 rounded or semi-circular while the exterior of the back is flat while as to the beard its front face is substantially semicircular and its inner or rear face is flattened.

What I claim is:—

1. A spring beard needle having a flexible back, the rear face of which is substantially flat, and its front face rounded, a nose of circular cross section and a beard rounded on its outer or front face and a substantially flat inner face, substantially as described. 70

2. A spring beard needle having the upper portion of its stem back of the beard inclined rearwardly in relation to the main 75 part of the stem, its rear face cut away, a stiffened nose and a flexible beard, substantially as described.

3. A spring beard needle having a flexible beard, a flexible stem portion back of the beard wider than deep in cross section, and a nose of circular cross section and non-flexible, substantially as described. 85

4. A spring beard needle having its back or stem lying opposite the beard of reduced thickness in respect to the main part of the stem, said reduced portion having its rear face curved longitudinally and of minimum thickness at a point intermediate the length of said reduced portion or below the point of juncture of said portion with the nose of the needle, substantially as described. 90

5. A spring beard needle having its back

or stem in rear of the beard of reduced thickness, said portion having its rear face curved longitudinally and of minimum thickness at a point intermediate the length of said reduced portion or below the point of juncture of said portion with the nose of the needle, said nose being circular in

cross section and of one diameter throughout the semi-circular bend forming said nose.

16

In testimony whereof, I affix my signature.

ALBERT M. PIGEON.
